UNITED STATES PATENT OFFICE.

WILLIAM KELSO, OF PITTSBURGH, PENNSYLVANIA, ASSIGNOR TO THE MC CONWAY & TORLEY COMPANY, OF PITTSBURGH, PENNSYLVANIA, A CORPORATION OF PENNSYLVANIA.

CAR COUPLER.

Application filed May 10, 1922. Serial No. 559,814.

To all whom it may concern:

Be it known that I, WILLIAM KELSO, a citizen of the United States, residing at Pittsburgh, in the county of Allegheny and

5 State of Pennsylvania, have invented certain new and useful Improvements in Car Couplers; and I do hereby declare the following to be a full, clear, and exact description of the invention, such as will enable 10 others skilled in the art to which it appertains to make and use the same.

My invention relates to car couplers of the Master Car Builders' type, and while the features of improved construction hereinafter described and claimed are not limited in application to the particular coupler known as the Master Car Builders' standard D-coupler, the principal object of the invention is to perfect and improve the D- 20 coupler so as to render it reliable in service.

In the D-coupler the outward rotation of the knuckle is restrained by means of a vertically sliding and rearwardly swinging lock which rests upon a horizontally rotatable knuckle opening lever when the parts 25 are in locked position. While this form of coupler is provided with means intended to prevent accidental unlocking of the knuckle, the nature of the parts and their mode of 30 combination in the structure are such that under certain circumstances the lock may accidentally move to an unlocked position. The specific object of the invention is to remedy this defect.

35 In the drawings, which illustrate my invention as applied to the Master Car Builders' standard D-coupler,—

Figure 1 is a horizontal sectional view of the mechanism, the knuckle opening lever being in plan and a portion of the stem of 40 the coupler being broken away.

Figure 2 is a sectional view on the line 2—2, Fig. 1, the lock, knuckle opener and knuckle being shown in elevation and the 45 lock being illustrated in the position it is designed to assume when the parts are in locked relation.

Figure 3 is a detail view corresponding to Fig. 2 but illustrating another locked position which the coupler lock may assume 50 in service.

Figure 4 is a detail view corresponding to Fig. 3, but illustrating the relative positions assumed by the lock and its actuating 55 mechanism when the latter is caused to per-

form the preliminary movement for releasing the lock from the control of the means by which its accidental unlocking is prevented.

Figure 5 is a detail elevation of the lock 60 actuating link.

Figure 6 is an elevational view of the lock actuating link taken at right angles to Fig. 5.

Figure 7 is a detail sectional view on the line 7—7 Fig. 2.

In the drawings, 1 indicates the coupler head and 2 is the knuckle pivotally mounted thereon by means of the knuckle pin 3. Outward rotation of the knuckle is restrained by a vertically sliding and rearwardly swinging lock 4 which, when in locked position, is supported upon a horizontally rotatable knuckle opening lever 5 with which the coupler is provided. The 75 upper part of the lock 4 extends across the path of movement of the tail of the knuckle while its lower portion is fashioned as a depending leg 6 extending downwardly through an opening 7 in the lower wall of 80 the coupler head. When the lock 4 is swung rearwardly after having been elevated sufficiently to permit outward rotation of the knuckle 2, the depending leg 6 presses rearwardly against the adjacent end of the 85 knuckle opener 5, thereby effecting a rotation of the latter and a consequent uncoupling rotation of the knuckle.

In the D-coupler the position assumed in service by the lock 4 is controlled by that assumed by the knuckle opening lever 5 and by the extension 18 on the back of the wall forming the face of the coupler head 1. If the knuckle opener is in the position shown in Fig. 1 and all the parts are to exact standard dimensions, the coupler lock 4 when in locked position will occupy the relation to the coupler head illustrated in Fig. 2. The position which the knuckle opener assumes, however, is affected by the lug 19 on the under side of the knuckle 2, as it is this lug which comes into contact with the end of the knuckle opener 5 and causes a rotation of the knuckle opener during a closing rotation of the knuckle. It will be appreciated that the coupling rotation of the knuckle may be performed with proper speed to return the knuckle opener to the position shown in Fig. 1, but if the knuckle is rotated slowly inward the end of the knuckle opener 5 may remain 105 110

in contact with the lug 19 when the knuckle is fully closed, and should the knuckle be closed very rapidly and violently the knuckle 5 opener may have sufficient momentum im- parted to it to rebound toward the lug 19 of the knuckle. When the end of the knuckle opener which is behind the knuckle tail stands away from the adjacent wall 20 of the coupler head, the lock when in locked po- 10 sition may occupy the position illustrated in Fig. 3, thereby causing the lock-to-the-lock devices with which the standard D-coupler is provided to shift with respect to each other in a manner resulting in rendering 15 them ineffective to perform their intended function of preventing accidental unlocking of the coupler lock 4. The effect of this possible movement of the knuckle opener is augmented by the necessary working clear- 20 ances of the parts, by slight though allow- able variations in the dimensions of the coupler head and movable parts of the coupler, and by even a comparatively small amount of wear, which latter necessarily in- 25 creases during the life of the coupler. By my improvement this defect in the D-coupler is overcome and the coupler lock 4 in what- ever locked position it may assume is pre- 30 vented from accidentally moving to un- locked position.

The lock 4 is actuated to perform its vertically sliding and rearwardly swinging movements through the instrumentality of a link 8 pivotally connected at 9 to a lock- 35 actuating lever 10 that is itself pivotally connected at 11 to the under side of the coupler head in a well known manner. The link 8 is formed at its upper end with a trans- versely extending pin 12 projecting into an 40 inclined slot 13 with which the depending leg 6 of the lock is furnished at its lower end, the said link thereby being both slid- ably and rotatably connected to the lock 4.

Extending forwardly beyond the pin 12 45 and preferably adjacent said pin, the link 8 is provided with a shoulder 14 which may advantageously slope downwardly and for- wardly. By so inclining the shoulder 14 the extent of accidental upward movement 50 which the lock 4 may have, before the lock is arrested by the shoulder coming in contact with the overlying shelf or shoulder 15 of the coupler head, is rendered compa- 55 ratively slight not only when the depending leg 6 of the lock stands in the position illus- trated in Fig. 2, but also in case the said leg occupies the locked position shown in Fig. 3. The forward end of the inclined shoulder 14 is preferably slightly beveled or rounded, as 60 at 16, so that during a normal unlocking operation of the link 8 the inclined shoulder 14 may readily clear the inner end of the shelf 15 after the leg 6 of the lock has been forced to execute a movement toward the 65 coupler head wall 17 by which the rearward

movement of the said leg is limited when the coupler is locked.

To the end that the cam action of the link 8 upon the shelf 15 when the parts are automatically returning to locked position after 70 the coupler has been unlocked shall not be required to enforce such an extended rear- ward movement or vibration of the lock leg 6 as might render the locking operation of the parts unduly sluggish, the inclined 75 shoulder 14 of the link preferably does not extend forwardly beyond the pin 12 so far as to necessitate the leg 6 assuming its rear- most position in order to permit the upper end of the link to pass between the locking 80 shelf 15 and the wall or lug 17 of the coupler head.

From an inspection of Figs. 2 and 3 it will be perceived that the link 8 with its shoulder 14 forms in conjunction with the 85 shoulder 15 of the coupler head a lock-to- the-lock mechanism which efficiently pre- vents accidental unlocking of the coupler in all positions which the lock 4 may assume when the parts are in coupled relation. 90

When the lock-actuating lever 10 is swung upwardly in the act of unlocking the coupler the pin 12 at the upper end of the link 8 slides rearward in the inclined slot 13 at the lower end of the leg 6 of the lock and upon reach- 95 ing the rear end of said slot causes the said leg to swing toward the stop portion 17 of the coupler head sufficiently far to permit the shoulder 14 to clear the shelf 15, pro- vided the leg 6 is not already in such a rear- ward position. Upon the shoulder 14 of the link thus being withdrawn from beneath the overlying shoulder 15 of the coupler head, the continued upward movement of the lever 10 and link 8 effects an extended unlocking 100 movement of the coupler lock. 105

I claim:—

1. In a car coupler, the combination with a coupler head, a knuckle, and a vertically sliding and rearwardly swinging lock for said knuckle, of a lever pivoted to the under side of the coupler head, and a lock-actuating link pivotally connected to said lever and slidably and rotatably connected to said lock, said lock being provided with a de- 110 pending leg having an inclined slot there- in, said coupler head having a stop portion extending behind said leg to limit rearward movement thereof when the lock is in locked position, said link being formed at its up- 115 per end with a pin extending into and move- able in the direction of length of said slot and also being provided at its upper end with a forwardly and downwardly inclined shoulder, and said coupler head being pro- 120 vided with a shoulder extending over said link inclined shoulder in all positions of said link when said depending leg is in its forward position. 125

2. In a car coupler, the combination with 130

a coupler head, a knuckle, and a vertically sliding and rearwardly swinging lock for said knuckle, said lock being provided with a depending leg having an inclined slot 5 therein, and said coupler head having a stop portion extending behind said leg to limit rearward movement thereof when the lock is in locked position, of a link for actuating said lock, said link being formed at its upper end with a pin extending into and movable in the direction of length of said slot, and also being provided with a shoulder extending forwardly beyond said pin, and said coupler head being provided with a portion 10 extending over said shoulder in all positions of said link when said depending leg is in its forward position.

3. In a car coupler, the combination with a coupler head, a knuckle, and a vertically sliding and rearwardly swinging lock for said knuckle, said lock being provided with a depending leg, of means for actuating said lock, and means cooperating with said lock-actuating means and serving, when said depending leg is in its forward position, to prevent upward movement of said lock until after said leg has been moved rearwardly by 15

the normal manual operation of said lock-actuating means.

4. In a car coupler, the combination with a coupler head, a knuckle, and a vertically sliding and rearwardly swinging lock for said knuckle, said lock being provided with a depending leg having an inclined slot 30 therein, and said coupler head having a stop portion extending behind said leg to limit rearward movement thereof when the lock is in locked position, of a link adapted to actuate said lock, said link being formed at its upper end with a pin extending into and 35 movable in the direction of length of said slot and having a shoulder extending forwardly beyond said pin, and a shoulder on said coupler head cooperating with the shoulder of said link when said depending leg is in its forward position to prevent an upward unlocking movement of said lock until after said leg has been moved rearwardly by the normal manual operation of 40 said link.

5. In testimony whereof I affix my signature.

WILLIAM KELSO.
